(57) **CLAIM**

The ornamental design for a pet blanket as shown and described.

DESCRIPTION

FIG. 1 is a perspective view of a first side of the pet blanket;

FIG. 2 is a top plan view thereof;

FIG. 3 is a bottom plan view thereof;

FIG. 4 is a first side view thereof;

FIG. 5 is a second side view thereof;

FIG. 6 is a first end view thereof; and,

FIG. 7 is a second end view thereof.

The thin solid lines in the views have been provided for the purpose of illustrating the texture and contour of the surfaces of the pet blanket.
